Primary Examiner—Susan Moon Lee*(74) Attorney, Agent, or Firm*—Antoinette G. Giugliano, PC**CLAIM**

The ornamental design for a pet bowl, as shown.

DESCRIPTION

FIG. 1 is a front perspective view of a pet bowl showing my new design;

FIG. 2 is a top plan view thereof;

FIG. 3 is a bottom plan view thereof;

FIG. 4 is a front side elevational view thereof;

FIG. 5 is a rear side elevational view thereof;

FIG. 6 is a left side elevational view thereof; and,

FIG. 7 is a right side elevational view thereof.

The portions shown in broken line are not claimed.
